United States Patent Office.

EDWARD S. KENNEDY, OF BIRMINGHAM, (BUCHANAN POST OFFICE,) PENNSYLVANIA.

Letters Patent No. 110,473, dated December 27, 1870.

IMPROVEMENT IN SPICE-BOXES.

The Schedule referred to in these Letters Patent and making part of the same.

To all whom it may concern:

Be it known that I, EDWARD S. KENNEDY, of Birmingham, (Buchanan post office,) in the county of Allegheny and State of Pennsylvania, have invented a new and useful Improvement in Spice-Boxes; and I do hereby declare that the following is a full, clear, and exact description thereof, which will enable others skilled in the art to make and use the same, referring, however, to the accompanying drawing forming part of this specification, in which—

Figure 1 is a detail sectional view of my improved spice-box.

Figure 2 is detail cross-section of the same taken through the line xx , fig. 1.

Similar letters of reference indicate corresponding parts.

My invention has for its object to furnish an improved spice-box, which shall be so constructed as to contain salt and pepper or two other spices, and which shall at the same time be simple in construction and convenient in use; and

It consists in the construction and combination of the various parts of the device as hereinafter more fully described.

A represents the box or receptacle, which is made with a compartment in each end, to contain the salt and pepper or other spices.

The box A may be made of glass or other suitable material; but when made of glass should have a metallic band around its middle part, to receive the pivots B, by which the said box A may be pivoted to a stand, C.

The stand C is formed of a U-shaped standard, c¹, and base, c², the arms of the standard projecting up upon the opposite sides of the box A, and have bearings formed in them to receive the pivots B.

The upper part of the bearings is made detachable, and is secured with a screw, so that the box may be readily detached when desired.

The box A may be used without the stand C when desired.

In this case the pivots B may be omitted, or replaced by or changed into a handle.

The mouth of the compartment that is designed to contain the salt may be made larger than the mouth

of the other compartment, so as to give a more abundant discharge to the substance, of which a greater quantity is used.

Upon the mouths of the compartments of the box A are placed caps D, which may be secured in place by means of a screw-thread in the said cap fitting into a screw-thread formed upon the end of the said box, as shown in the case of the smaller cap D. Or the caps D may be formed to fit closely upon the end of the box, so as to be held by friction, as shown in the case of the larger cap D.

The plate of the caps D is perforated with holes, through which the salt and pepper or other spice may escape.

E are disks or plates placed within the caps D, and pivoted at their centers to the centers of the tops of the said caps D by a rivet.

Upon the edge of the plates E is formed an arm, F, which projects through a slit in the sides of the caps D, and by means of which the said plates E may be adjusted.

The plates E are perforated with holes corresponding in number, size, and position with the holes through the caps D, so that when the said plates E are turned into one position the discharge-openings may be wholly closed, and when the said plates are turned into the other position the contents of the box may be discharged freely.

Having thus described my invention,

I claim as new and desire to secure by Letters Patent—

1. The spice-box A, made with two compartments and provided with caps D and adjustable perforated plates E F, whether used with or without a stand, substantially as herein shown and described, and for the purpose set forth.

2. The combination of the box A, made with two compartments, caps D, perforated pivoted plates E F, pivots B, and stand C, with each other, said parts being constructed and operating substantially as herein shown and described, and for the purpose set forth.

EDWARD S. KENNEDY.
